UNITED STATES PATENT OFFICE.

JOHN H. MELAVIN, OF CAMBRIDGEPORT, ASSIGNOR TO THE BOSTON WOVEN HOSE AND RUBBER COMPANY, OF BOSTON, MASSACHUSETTS.

DESIGN FOR A NOZZLE FOR LAWN-SPRINKLERS.

SPECIFICATION forming part of Design No. 22,491, dated May 30, 1893.

Application filed March 20, 1893. Serial No. 466,947. Term of patent 7 years.

To all whom it may concern:

Be it known that I, JOHN H. MELAVIN, of Cambridgeport, in the county of Middlesex and State of Massachusetts, have invented 5 a certain new and original Design for a Nozzle for Lawn-Sprinklers, of which the following is a specification.

The figure of the drawing is a perspective view, showing my design.

10 The essential feature of my design consists of a cylindrical body, a flat top with an opening in the center having flaring sides and a base which flares outwardly and downwardly, and is scalloped at its edges.

15 In the drawing *a* is the body of the sprinkler which is cylindrical in its general contour.

b is the top which is flat, the sides *c* of the opening in the center being flaring.

e is the base which flares outwardly and downwardly from the body and is scalloped 20 at its edges, as at *f*.

g is the inlet of rounded contour projecting laterally from the body *a*.

What I claim is—

The design for a nozzle for lawn sprinklers, 25 substantially as herein shown and described.

In testimony whereof I have signed my name to this specification, in the presence of two subscribing witnesses, this 4th day of March, A. D. 1893.

JOHN H. MELAVIN.

Witnesses:

ARTHUR W. CROSSLEY,
A. D. HARRISON.
